US00D546410S

(12) **United States Design Patent** (10) **Patent No.:** **US D546,410 S**
Wiesener et al. (45) **Date of Patent:** **** Jul. 10, 2007**

(54) **DEFLECTION DEVICE FOR BIRDS**

(75) Inventors: **Mark Wiesener**, Berlin (DE); **Bernd Wiesener**, Berlin (DE)

(73) Assignee: **UrbanGuard GmbH**, Berlin (DE)

(**) Term: **14 Years**

(21) Appl. No.: **29/230,506**

(22) Filed: **May 23, 2005**

(51) **LOC (8) Cl.** **22-06**

(52) **U.S. Cl.** **D22/120; D30/199**

(58) **Field of Classification Search** **428/131-32, 428/136, 119, 577, 596-97, 907; D22/120; 72/335; 83/40, 41, 49; 52/101, 60; 119/52.3, 119/57.9, 713, 903; 256/11; 43/1, 124, 58; 116/22 A; D30/199**

See application file for complete search history.

(57) **CLAIM**

The ornamental design for a deflection device for birds, as shown and described.

DESCRIPTION

FIG. 1 is a side top front perspective view of a deflection device for birds showing our new design;

FIG. 2 is a top perspective view thereof;

FIG. 3 is an enlarged partial front perspective view thereof; and,

FIG. 4 is a further enlarged partial detail view thereof.
